UNITED STATES PATENT OFFICE

112,010

DESIGN FOR A TIE

Cullen J. Watt, Carpinteria, Calif.

Application April 8, 1938, Serial No. 76,389

Term of patent 14 years

To all whom it may concern:

Be it known that I, Cullen J. Watt, a citizen of the United States, residing at Carpinteria, in the county of Santa Barbara and State of California, have invented a new, original, and ornamental Design for a Tie, of which the following is a specification, reference being had to the accompanying drawing, forming part thereof.

The figure is a plan view of a tie showing my new design.

I claim:

The ornamental design for a tie, as shown.

CULLEN J. WATT.
